[57] CLAIM

The ornamental design for a base for a telephone set, substantially as shown and described.

DESCRIPTION

FIG. 1 is a top, right side and front perspective view of a base for a telephone set, showing my new design;

FIG. 2 is a top plan view thereof;

FIG. 3 is a front elevational view thereof;

FIG. 4 is a bottom plan view thereof;

FIG. 5 is a rear elevational view thereof; and,

FIGS. 6 and 7 are respectively right and left side elevational views thereof.

FIG. 1

FIG. 2

FIG. 3

FIG. 4

FIG. 5

FIG. 6

FIG. 7
